(57) **CLAIM**

The ornamental design for a seat frame, as shown and described.

DESCRIPTION

FIG. 1 is a perspective view of a seat frame in accordance with the new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top view thereof;

FIG. 7 is another perspective view of the seat frame thereof configured as a swivel rocker;

FIG. 8 is another perspective view of the seat frame thereof having indeterminate width;

FIG. 9 is another perspective view of the seat frame thereof having indeterminate width;

FIG. 10 is another perspective view of the seat frame thereof configured as a sling arm chair;

FIG. 11 is another perspective view of the seat frame thereof configured as a sling swivel rocker;

FIG. 12 is another perspective view of the seat frame thereof configured as a chaise;

FIG. 13 is another perspective view of a seat frame with portions having different colored surfaces in accordance with another aspect of the new design;

FIG. 14 is a front elevational view thereof;

FIG. 15 is a left side elevational view thereof;

FIG. 16 is a right side elevational view thereof;

FIG. 17 is a rear elevational view thereof; and,

FIG. 18 is a top view thereof.

The broken lines in the figures are for illustration purposes only and form no part of the claimed invention.

1 Claim, 18 Drawing Sheets
